UNITED STATES PATENT OFFICE

168,450

CABINET FOR A HEATER OR THE LIKE

Max E. Hosmer, Lansing, Mich., assignor to Motor Wheel Corporation, Lansing, Mich., a corporation of Michigan

Application November 17, 1951, Serial No. 17,460

Term of patent 7 years

(Cl. D81—19)

To all whom it may concern:

Be it known that I, Max E. Hosmer, a citizen of the United States, residing at Lansing, in the county of Ingham and State of Michigan, have invented a new, original, and ornamental Design for a Cabinet for a Heater or the like, of which the following is a specification, reference being made to the accompanying drawing, forming part thereof.

Fig. 1 is a perspective view of a cabinet for a heater or the like, showing my new design.

Figs. 2 and 3 are sections along the lines 2—2 and 3—3 respectively of Fig. 1.

The side of the cabinet not shown and the back of the cabinet are both plain. The essential features of the design reside in those portions shown in full lines.

I claim:

The ornamental design for a cabinet for a heater or the like, substantially as shown and described.

MAX E. HOSMER.
